UNITED STATES PATENT OFFICE.

WILLIAM FREDERICK, OF NEWCASTLE, PENNSYLVANIA.

DESIGN FOR A VIOLIN-BODY.

SPECIFICATION forming part of Design No. 35,095, dated September 17, 1901.

Application filed June 21, 1901. Serial No. 65,510. Term of patent 7 years.

To all whom it may concern:

Be it known that I, WILLIAM FREDERICK, a citizen of the United States of America, residing at Newcastle, in the county of Lawrence and State of Pennsylvania, have invented and produced a new and original Design for a Violin-Body; and I do hereby declare the following to be a full, clear, and exact description thereof, reference being had to the accompanying drawings, which form a part of this specification.

This invention relates to certain new and original designs in violins; and it consists in the novel form, configuration, and shape of violin, all of which will be herein explained in detail.

In the drawings, Figure 1 is an enlarged side elevation of my new and original design. Fig. 2 is a vertical sectional view taken on the line 2 2 of Fig. 1. Fig. 3 is a contracted plan view of my design.

Referring to the drawings by reference-numerals, 1 indicates the body portion of the violin, which is formed of curved lines 2 and 25 a curved bottom 3, the outer contour of the body portion being curved inwardly, as shown

at 4, and having openings formed therein, (indicated by the reference-numeral 5.)

The reference-numeral 6 indicates a finger-board having a downwardly-curved point 7, 30 upon which is arranged an ornamental head 8.

The reference-numeral 14 indicates a cut-away portion on the one side of the body portion.

It will be seen that the herein-described 35 violin presents a most novel and attractive appearance to the eye and is composed of straight and curved lines, as shown, having attached thereto an ornamental head that further adds to the appearance of the design. 40

Having fully described my invention, what I claim as new, and desire to secure by Letters Patent, is—

The design for a violin-body, substantially as herein shown and described. 45

In testimony whereof I have hereunto affixed my signature in the presence of two subscribing witnesses.

WILLIAM FREDERICK.

Witnesses:

JOHN GROETZINGER,
M. HUNTER.
